UNITED STATES PATENT OFFICE

2,489,874

THAWING SYSTEM FOR RAILWAY CARS

Walter C. Elze and Alexander J. Turpin, Forest Hills Gardens, N. Y., assignors to Hauck Manufacturing Company, Brooklyn, N. Y., a corporation of New York

Application March 8, 1945, Serial No. 581,646

4 Claims. (Cl. 104—51)

1

The invention relates to thawing systems for use with railway cars, more especially of the hopper type with bottom dump, such as cars for transporting coal and like broken materials which may become frozen during the winter season into a solid mass. Considerable difficulty may be experienced in loosening such solidified mass not only as to the individual particles but as well in loosening the material from the container, also in the opening of the dump doors thereof. Various expedients have been resorted to in attempting such thawing, for example, streams of steam have been directed to the car as well as jets of flame from suitable burner apparatus, and pounding with suitable implements. While these means may be effective to a certain degree at particular portions of the solidified mass, such as those in the region of immediate contact by a stream or blow, a general thawing and loosening of the entire mass is not satisfactorily attained, and the operation, also, requires continuous personal attention and an undue amount of time.

The present invention has for an object to expedite such thawing operations and to bring about a more uniform action in the loosening operation by providing for a combined radiation and convection effect of a gaseous heating medium, with extended area of application of the same.

Another object of the invention is to provide means whereby thawing operations of the nature set forth may progress with minimum personal attention, once the heating has been initiated.

Still another object is to provide an open-top pit or combustion chamber adapted for association with the car whose contents, as well as the hopper portion of said car, are to be thawed.

The invention has for an object, also, to provide an open-top pit with combustion chamber designed to be installed between the two rails of the track over which a car may be run and located thereover for the thawing operation; and to provide to this end burner members upon opposite sides of the track outside the rails thereof for directing oppositely into the said combustion chamber air with combustible media for effecting combustion of such media therein.

A further object is to so mount the burner members with respect to an associated combustion chamber that the streams provided by these burner members will be delivered therein displaced in a direction longitudinally of the track and be also directed substantially to diagonally opposite corners of said combustion chamber.

A still further object is to provide the stream-

2

receiving corners of the combustion chamber with a surface having a contour such as to impart to the products of combustion and/or combustible mixture a swirling or rotary movement for more intimate mixture thereof and to reduce exit velocity of these gases, as well as to cause them to be deflected upwardly through the open top of the pit, thereby to secure a more equal distribution of said products of combustion over the full area of opening rather than a delivery therefrom of jets of flame.

Another object is to associate suitable housings with the combustion chamber for accommodating the respective burner members at opposite sides of the track and provide openings therefrom to the combustion chamber for introducing into the chamber the discharges from the burner members.

In carrying out the invention, a more or less 20 elongated or rectangular pit is set transversely below a track in a depression provided in the roadbed which has first been cleared of one or more of the usual ties as may be required, the combustion chamber portion of the pit being 25 located between two rails of said track and being open at the top and extended upwardly to terminate in an outlet located slightly below the running surface of the rails so as to avoid possible load thereon. At both sides, the combustion chamber is flanked by secondary chambers located outside the corresponding rails, said chambers housing suitable burner members and control mechanism therefor. The walls between the combustion chamber and these secondary chambers are depressed substantially below the running surface of the rails where they pass under said rails and adjacently thereto the pit wall portions afford supporting shoulders for rail securing plates.

The burner members are designed to deliver 30 into the combustion chamber, from opposite ends and through suitable openings provided in said common walls, streams of combustible mixtures and/or flames and in a manner such that the respective jets will not directly collide therein. The openings to this end are displaced therein 35 longitudinally of the track. The streams are directed preferably to diagonally opposite corners of the combustion chamber, which corners, preferably, also are of such construction or contours that a swirling or rotary movement will be imparted thereby to the introduced streams and also an upward deflection toward the top outlet of the said combustion chamber.

The nature of the invention, however, will

best be understood when described in connection with the accompanying drawings, in which:

Fig. 1 is a plan view of a section of railroad track equipped with a battery of the novel heating pits.

Fig. 2 is a detail plan view of a pit-equipped section of track.

Fig. 3 is a longitudinal section taken on the line 3—3, Fig. 2, looking in the direction of the arrows; and Fig. 4 is a similar and transverse section with a portion broken away, taken on the line 4—4, Fig. 3 of the drawings.

Referring to the drawings, an installation of the novel thawing system is shown in Fig. 1, and comprises a succession or battery of pits 10 arranged transversely of a section of track having rails 11 and 12, the usual ties for which have been replaced by shoulder portions 13 and 14, adjacent depressed portions of the end walls of the combustion chamber 15 of the pit. These shoulders carry rail securing plates 16 and 17, respectively, of well known design and adapted to fasten or hold down a rail in the usual manner. One, or more, of the pits is designed to take care of a car (not shown) which is to be run over the track to the particular location of a pit or pits so that heat from the outlet 18 of a pit passes both by radiation from the interior walls of the pit and by convection of the products of combustion directly to the underside of a car and in the vicinity of the bottom dump thereof when thus equipped.

In installing the novel thawing pits, a depression of ample size is prepared in the roadbed, first removing the required number of ties, to permit of pouring or sinking a pit into the depression such that when the rails have been laid thereover an intermediate or combustion chamber 15 may be located between the rails 11 and 12. This chamber is preferably constructed of suitable refractory material such as fire-brick and the like and it extends upwardly between the rails to provide the outlet 18 which terminates slightly below the running surfaces of said rails so that no excessive load, as from a car, will be applied to the pit. The pits are constructed, preferably, of rectangular shape and are disposed transversely of the rails with inclined approach portions 20 between the rails at the sides of the pit. Respective openings or ports 21 and 22 are provided in the end walls of a combustion chamber 15 at the lower portion thereof, for the purpose hereinafter set forth, and to afford communication between the combustion chamber and second chambers 23 and 24 which flank said combustion chamber and are situated beyond the corresponding rails. At the outer end of a said port or communication a sealing plate or mounting bracket 25 and a similar plate or mounting bracket 26 are provided on the common walls between the combustion chamber and the secondary chambers, and they have openings therethrough coaxial with the corresponding ports. These openings are adapted to receive the nozzle end of burner members 27 and 28 for discharge through said ports into the combustion chamber of combustible mixtures, for example, of fuel gas and air, or powdered solid fuel and air, or of flames from said burners.

Mains 30 for the fuel and mains 31 for air parallel the track; and at intervals, corresponding to the number of pits, branches are taken therefrom and pass through channels or depressions 32 and 33 in the side walls of the pit to the corresponding secondary chambers to supply the

burner members 27 and 28 therein. The usual fuel metering and control means are associated with these supply mains and branches while, preferably, in the secondary chambers are located the immediate shut-off valves 34 and 35—all of which control and connection arrangements are well understood and no invention is claimed for the same herein.

To avoid direct collision within a combustion chamber 15 between the entering streams or jets of combustible mixture and/or flames, the ports 21 and 22 are staggered or displaced therein longitudinally of the track, as indicated in Fig. 2 of the drawings, and, further, are directed to diagonally opposite corners 36 and 37 of a chamber. These corners are finished to a curved or toroidal surface of impact for the respective streams, thereby causing the same to be swirled or rotated in a substantially horizontal plane as well as to be deflected upwardly toward the outlet opening 18 to secure a more equal distribution of products of combustion over a full area, as well as to reduce the exit velocity of these products. This will provide for more effective thawing action which is accomplished in the novel arrangement both by radiation from the highly heated inner walls of the combustion chamber and by convection of said products of combustion to a car located over said outlet opening 18. No flame, furthermore, is likely to contact a car body.

We claim:

1. In a system for thawing from below railway cars while located on a track, the combination with a pit, set in a depression below the track, affording a combustion chamber between the rails of the track and flanked on each side by secondary chambers located outside the tracks and having openings affording communication with the combustion chamber, said openings being displaced with respect to each other longitudinally of the track; of burner members including control means therefor housed in the respective secondary chambers and adapted for discharge through the corresponding openings into said combustion chamber and respectively against opposite walls.

2. The thawing system as claimed in claim 1, wherein the openings between respective secondary chambers and the combustion chamber are located so as to direct streams of combustible mixture and/or flame to diagonally opposite corners of said combustion chamber.

3. The thawing system as claimed in claim 1, wherein the openings between respective secondary chambers and the combustion chamber are located so as to direct streams of combustible mixture and/or flame to diagonally opposite corners of said combustion chamber and said corners are of toroidal contour for deflecting the streams both in a horizontal plane and in a vertical plane.

4. In a system for thawing from below railway cars while located on a track, the combination with a substantially rectangular pit, set in a depression below the track transversely thereof, affording a combustion chamber which extends upwardly between the rails slightly below the running surface thereof, to provide an outlet for products of combustion, the tops of the end walls of the combustion chamber being depressed over a portion, the adjacent pit walls providing shoulders for supporting the rails, and the combustion chamber being flanked on each side by secondary chambers located outside the tracks and having

openings through the respective end walls affording communication with the combustion chamber, said openings being displaced with respect to each other longitudinally of the track so as to direct streams of combustible mixture and/or flame to diagonally opposite corners of said combustion chamber and said corners being of toroidal contour for deflecting the streams both in a horizontal plane and in a vertical plane; of burner members, including control means therefor, housed in the respective secondary chambers and adapted for discharge through the

corresponding openings into said combustion chamber.
